(57) **CLAIM**

I claim the ornamental design for an apparatus for removing an intraoral device, as shown and described.

DESCRIPTION

FIG. 1 is a first perspective view as seen from the upper right of an apparatus for removing an intraoral device, showing my new design;

FIG. 2 is a second perspective view thereof;

FIG. 3 is a third perspective view thereof, showing cutline 11-11;

FIG. 4 is an enlarged perspective partial view thereof;

FIG. 5 is a front side view thereof;

FIG. 6 is a right side view thereof;

FIG. 7 is a left side view thereof;

FIG. 8 is a back side view thereof;

FIG. 9 is an enlarged bottom side view thereof;

FIG. 10 is an enlarged top side view thereof; and,

FIG. 11 is an enlarged cross sectional view taken along line 11-11 of FIG. 3.
